EVENER FOR DRAFTING MECHANISMS

Joe R. Whitehurst, Bessemer City, N. C., assignor to Ideal Industries, Inc., Bessemer City, N. C., a corporation of North Carolina

Application November 14, 1952, Serial No. 320,498

4 Claims. (Cl. 19—130)

This invention relates to apparatus, for drawing or drafting textile strands of roving or sliver, of the type which is provided in association with drawing frames, spinning machines, roving machines and the like, and it is the primary object of this invention to provide an evener apparatus in conjunction with the drawing rolls wherein a plurality of strands of sliver or roving are drafted simultaneously, which evener varies the speed at which each strand is fed through the drawing rolls in accordance with variations in the density and/or thickness of the individual strands so the strands issuing from between the delivery rolls, although attenuated, have greater uniformity than do the original strands.

As is well known to those familiar with the art, drawing frames comprise a series of pairs of intermeshing fluted rolls, positioned one pair in advance of another, through which a plurality of strands of roving are fed, each successive pair of rolls being driven at a slightly higher peripheral speed than the preceding pair so as to produce the desired draft. The attenuated strands issuing from between the delivery rolls are gathered into a trumpet and fed into a coiler.

Now, the density and/or thickness of each individual strand is inconsistent throughout its length in advance of being drafted and one strand might have closely adjacent successive thick and thin places therein while an immediately adjacent strand may have relatively thick places spaced substantially far apart from each other and, also, the thick places are irregularly interspersed through the length of each strand. Accordingly, heretofore, this unevenness in the strands would be more pronounced after the strands had been drafted than before they were drafted due to the fact that all of the strands were caused to pass through the drawing rolls at the same speed regardless of any variations in density and/or thickness of the individual strands.

It is therefore another object of this invention to provide, in a machine having a plurality of sets of top and bottom drawing rolls, a fluted common bottom feed roll spaced in advance of the bottom roll of a first set of top and bottom rolls, a plurality of relatively narrow fluted top feed rolls disposed above and meshing with the bottom feed roll with means for directing an individual strand of roving or sliver between each of the individual top feed rolls and the common bottom feed roll and with individual means for applying downward pressure to each of the top feed rolls so that the effective pitch diameters of the individual top feed rolls and the common bottom feed rolls are relatively increased and decreased as respective thick and thin places in the individual strands pass therebetween.

This results in the outer surfaces of the intermeshing flutes of the top and bottom feed rolls being spaced further from the corresponding roots or bottoms of the grooves defining said flutes when relatively thick places in the strands are passing therebetween than when relatively thin places in the strands are passing therebetween. Accordingly, the relatively thick places engage substantially

2

less surface area on the adjacent portions of the top and bottom fluted feed rolls than do the relatively thin places thereby causing relatively thick places in the strands to be fed at slower speeds than relatively thin places.

This causes the relatively thick places to be attenuated substantially more than the relatively thin places although relatively thick and thin places may pass between corresponding top feed rolls and the bottom feed roll simultaneously as they are directed to the next adjacent set of top and bottom drawing rolls.

It is obvious that, since the thick places are attenuated a greater amount than the thin places between the feed rolls and the succeeding set of top and bottom drafting rolls, the resultant strands issuing from the delivery rolls will have a greater uniformity than the original strands and, also, a greater uniformity than it has heretofore been possible to achieve with the conventional types of feed rolls; that is, wherein a common top feeding roll is provided for all of the strands.

Some of the objects of the invention having been stated, other objects will appear as the description proceeds, when taken in connection with the accompanying drawings in which—

Figure 1 is a fragmentary top plan view of a drawing frame showing one form of the improved evener apparatus in association therewith;

Figure 2 is a greatly enlarged illustration of a few strands of roving or sliver wherein variations in thickness or density of adjacent strands are exaggerated to illustrate the condition of such strands before they are passed through the improved evener mechanism in association with the drawing rolls of a drawing frame or the like;

Figure 3 is an enlarged view of the adjacent portions of one of the evener feed rolls and the corresponding bottom roll with a relatively thick or dense place in a strand of roving or sliver passing therebetween, the bottom roll being shown in cross-section;

Figure 4 is a view similar to Figure 3, but showing a relatively thin place in a strand of roving or sliver passing between the rolls;

Figure 5 is a vertical sectional view, mostly in elevation, taken substantially along the line 5—5 in Figure 1;

Figure 6 is a fragmentary perspective view looking at the rear end of one of the pivoted brackets which support the improved evener feed rolls and showing the relative positions of one of the evener feed rolls and the bottom feed roll;

Figure 7 is an enlarged vertical sectional view taken substantially along the line 7—7 in Figure 1 and showing the manner in which one of the improved evener feed rolls is mounted;

Figure 8 is a fragmentary vertical sectional view taken along the line 8—8 in Figure 7;

Figure 9 is a fragmentary sectional plan view, mostly in elevation, taken substantially along the line 9—9 in Figure 7 and showing one form of means for effecting downward pressure to the evener top rolls;

Figure 10 is a plan view similar to the left-hand portion of Figure 1, showing a modified form of means for supporting the pivoted brackets having the improved evener top rolls mounted therein;

Figure 11 is a fragmentary perspective view, with parts broken away, looking generally along the line 11—11 in Figure 10;

Figure 12 is a fragmentary vertical sectional view taken substantially along the line 12—12 in Figure 10;

Figure 13 is a fragmentary vertical sectional view taken substantially along the line 13—13 in Figure 10.

In the drawings the improved evener apparatus is shown in association with a textile drawing frame although it is to be understood that the improved evener apparatus may be used in association with any type of

textile machine having rolls for attenuating or drafting fibrous strands such as a spinning frame, roving frame or the like.

Referring first to Figures 1 and 5, the numeral 10 indicates spaced bearing stands which are suitably secured to a common frame member 11 and to the upper surface of each of which a plurality of substantially U-shaped bearing blocks 12 are adjustably secured, there being four of the bearing blocks 12 shown on each of the bearing stands 10.

Fluted bottom drawing rolls 13, 14, 15 and 16 are journaled in the bearing blocks 12, the bottom roll 13 being a feed roll, the rolls 14 and 15 being intermediate drawing or drafting rolls and the bottom roll 16 being a delivery drawing roll. The intermediate and delivery drawing rolls 14, 15 and 16 have respective intermediate and delivery top rolls 20, 21 and 22 resting thereupon and being journaled at opposite ends thereof in suitable corresponding bearings 23 mounted for vertical movement in the corresponding bearing blocks 12. The top rolls 20, 21 and 22 may also be fluted for as much of their length as the fluted portions of the respective bottom rolls 14, 15 and 16, as shown in Figures 1 and 5, or they may be covered with a suitable resilient material such as rubber, leather and the like as is well known to those familiar with the art.

The bottom rolls 13, 14, 15 and 16 are positively driven by suitable gearing, not shown, but the top rolls are driven generally through their relationship to the bottom rolls and through the intervening strands generally designated at S. The intermediate and front or delivery top rolls 20, 21 and 22 are resiliently urged downwardly against the respective bottom rolls 14, 15 and 16 by corresponding weight hooks 24 which bear on the bearing sleeves 23, and extend downwardly beneath the bottom rolls 14, 15 and 16 and are connected to suitable means which, in this instance, are shown in the form of leaf spring members 25 suitably secured to the lower surfaces of the horizontal portions 10a of the bearing stands 10.

These leaf spring members 25 may be substantially of the type disclosed in my co-pending application entitled Spring Pressure Means for Drafting Mechanisms, Serial Number 310,979, and filed September 23, 1952. The bottom feed roll 13 and each successive pair of rolls 14, 20, 15, 21 and 16, 22, proceeding from left to right in Figure 5 are driven at progressively higher speeds to produce the desired draft in the strands of roving or slivers S. A conventional cover 30 surmounts the drafting rolls or drawing rolls and is pivoted at its rear end, as at 31 on standards 32 carried by the bearing stands 10 and its front edge rests upon the front or foremost bearing blocks 12 in the usual manner.

The strands S are directed to the drawing rolls from a suitable source, not shown, and converge forwardly from the delivery rolls 16 and 22 and are gathered into a suitable trumpet 34 positioned above a pair of calender rolls 33 and 33a for directing the condensed strands S into a suitable container such as a can carried by a coiler, not shown. Each of the bearing stands 10 has a rearwardly projecting arm 36 integral therewith, to the upper surface of which a horizontal plate or apron 35 is suitably secured.

The parts heretofore described are conventional parts of a drawing frame or the like and it is with such an organization of parts that the present invention is adapted to be associated.

Heretofore, a top roll has been provided above the bottom feed roll 13 which was substantially the same as the top rolls 20, 21 and 22 and extended the full length of the top of the bottom feed roll 13. Accordingly, when the strands of slivers or roving S were directed between the bottom feed roll 13 and the corresponding top roll, any variations in the density or thickness of the strands would not individually affect the

effective pitch diameters of the top and bottom feed rolls. Thus, all of the strands would be fed to the succeeding set of drawing rolls which, in this instance, are the drawing rolls 14 and 20, at the same speed with the result that the slivers issuing from the delivery rolls 16 and 22, would still be uneven throughout their lengths as to density or thickness thereof.

Now, in order to correct this condition, I have provided a plurality of evener top rolls or evener feed rolls 37 which are arranged in a substantially axial row above and in engagement with the common bottom feed roll 13, there being one of these evener rolls 37 for each of the strands S. These rolls 37 are fluted about their peripheries, the spacing of the flutes on the individual evener rolls 37 corresponding to the spacing of the flutes on the common bottom feed roll 13.

Each of the evener rolls 37 is individually supported in a manner to be later described to permit movement thereof substantially radially of the bottom roll 13 so that, upon a relatively thick or dense place D (Figures 2 and 3) in one of the strands S passing beneath any one or more of the evener top rolls 37 as shown in Figure 3, and a relatively thin place T passing beneath any one or more of the other evener top rolls 37, as shown in Figure 4, the thick place D raises the corresponding roll or rolls 37 substantially further from the bottom roll 13 than the roll or rolls 37 are raised by the relatively thin places T.

The evener top rolls 37 are weighted or urged downwardly toward the bottom roll 13, by means to be presently described, and, accordingly, the flutes thereof force the corresponding strands S downwardly between the corresponding flutes of the bottom feed roll 13. Thus, it is evident that the relatively thin places T in the strands 35 are forced deeper into the grooves between adjacent flutes at the proximal surfaces of the evener top rolls 37 and the bottom roll 13 than are the relatively thick places D, requiring a substantially greater length of the sliver to pass between the adjacent surfaces of the rolls 13 and 37 at given surface speeds when a thin place T is passing beneath any one or more of the evener top rolls 37 than is the case when relatively thick places D are passing between the proximal portions of others of the evener top rolls 37 and the bottom feed roll 13.

It is therefore evident that the individual evener top rolls 37 cause the thin places to be fed between the same and the common bottom feed roll 13 at a faster speed than the thick places, as the slivers are pulled forwardly and attenuated by the succeeding set of drawing rolls 14 and 20, with the result that the relatively thin places T in each individual strand S are attenuated to a lesser degree than the thick places D in adjacent strands S. Thus, all of the strands S are of substantially uniform density and/or thickness as they pass from the first set of drawing rolls 14 and 20 and successively between the succeeding sets of drawing rolls 15 and 21 and 16 and 22 to the trumpet 34.

Since all of the evener rolls 37 are identical and are supported in the identical manner, only one of the evener rolls will be described in detail and all of the parts associated with each of the evener rolls 37 shall bear the same reference characters.

In the original form of the invention shown in Figures 1 and 5 to 9 inclusive, each of the top evener feed rolls 37 is made in the form of an externally fluted tubular shell which is fixed, as by a pressed fit, on an outer race 43 of an anti-friction bearing. The outer race 43 engages a pair of circular rows of balls 44. The balls 44 ride in corresponding peripheral grooves 45 in the periphery of a relatively short shaft 46 which, thus, serves as an inner race to the anti-friction bearing. Suitable lubricant seals 47 are provided at opposite ends of the outer race 43 to prevent lubricant from leaking from between the outer race 43 and the shaft 46. Although each evener top roll 37 is rotatably mounted on the shaft 46 by

means of an anti-friction bearing, it is to be understood that friction bearings may be utilized for this purpose, if desired.

Each of the shafts 46 is fixed at opposite ends thereof in spaced ears 50 of a bracket broadly designated at 51 and between which ears the corresponding evener top feed roll 37 is disposed. Each of the brackets 51 is preferably made from sheet metal, as shown in the drawings, but may be of cast or built-up welded construction if desired. The ears 50 extend rearwardly and are bent inwardly toward each other and formed integral with corresponding side wall portions 52 which are the legs of a U-shaped portion defining a trough 53 which is alined slightly below the juncture of the evener roll 37 and the common bottom feed roll 13 for directing the corresponding strand of roving or sliver S between the corresponding evener roll 37 and the common bottom feed roll 13.

The rear portion of each bracket 51 is bent downwardly at opposite sides thereof in a substantially inverted U-shaped manner to form spaced parallel ears 55 which are pivotally mounted on a pivot shaft 56. Opposite ends of the pivot shaft 56 are fixed in a substantially U-shaped clevis or standard 58 suitably secured, as by a bolt 57, to a transverse bar 60 disposed rearwardly of the bottom feed roll 13 and resting upon the plate 35.

All of the standards 58 are secured to the common bar 60 and the plate 35 is provided with a plurality of holes 61 which are arranged in forwardly and rearwardly extending rows for the reception of bolts 62 for adjustably securing the bar 60 to the plate 35. Since the relative positions of the drawing rolls must be varied according to the variations in the length of staple of the material forming the strands S, the holes 61 facilitate adjustment of the evener rolls 37 to correspond with forward and rearward adjustment of the bottom feed roll 13 relative to the roll stands 10. It is evident that the holes 61 may be formed as slots or the plate 35 may be provided with adjustment slots through which the bolts 62 extend, if desired.

There are various ways in which the top evener rolls 37 may be urged downwardly toward the common bottom feed roll 13 and the preferred means to this end is shown in Figures 5, 6, 7 and 9 wherein it will be observed that the rear end of the leaf spring member 64 is secured between each of the standards 58 and the bar 60 by means of the bolts 57 heretofore described. Each of the leaf spring members 64 has a relatively narrow tab 65 at the front end thereof which rests in a hook portion 66 of an upwardly extending rod 67. The upper end of the connecting rod 67 is provided with another hook portion 70 thereon which loosely penetrates a down-turned tab 71 at the front end of the trough 53. The length of the connecting rod 67 is such that the leaf spring member 64 is biased upwardly when flutes of the corresponding evener roll 37 are in engagement with the bottoms of the grooves between the flutes on the common feed roll 13. Thus, the evener rolls 37 are urged downwardly towards the common bottom roll 13.

Modified form of the invention

In Figures 10 to 13, inclusive, there is shown a modified or second form of the invention which differs from the other form of the invention shown in Figures 1, 5, 6, 7 and 9 only as to the manner in which the evener rolls are weighted and mounted for adjustment forwardly and rearwardly. Therefore, those parts which are identical in the modified form of the invention to the parts shown in the original form of the invention (Figures 1, 5, 6, 7 and 9) shall bear the same reference characters with the prime notation added.

In the form of the invention shown in Figures 10 to 13, inclusive, the standards 58' are secured directly to the upper surface of the common transverse bar 60', the

leaf spring members being omitted and, instead, each of the connecting rods 67' extends downwardly below the level of the plate 35' and has a weight member 75 fixed thereon to thus urge the evener roll 37' downwardly toward the common bottom feed roll 13'. The plate 35' is cut away to form an opening 76 therein through which the connecting rods 67 extend.

Now, in order to maintain the top evener feed rolls 37' in proper relation to the bottom feed roll 13' as the corresponding rearmost bearing blocks 12' are adjusted forwardly and rearwardly relative to the roll stands 10', opposite ends of the bar 60' each has an upwardly and forwardly projecting arm 77 integral therewith or suitably secured thereto and the front end of each of the arms 77 has an outwardly projecting journal portion 80 integral therewith which is of slightly less diameter than the width of the groove in the corresponding bearing block 12'. Thus, as the rearmost bearing blocks 12' are adjusted forwardly and rearwardly, to vary the position of the common bottom feed roll 13' relative to the succeeding sets of rolls and the roll stands 10', the lower surface of the bar 60' is caused to move in sliding engagement with the upper surface of the plate 35' to thereby maintain the evener feed rolls 37' in substantially vertical alinement with the common bottom feed roll 13'.

It is thus seen that I have provided a unique evener mechanism for drafting mechanisms to cause a plurality of adjacent strands of roving or sliver to be fed to the drafting rolls at varying speeds relative to each other according to variations in the thickness or density of the adjacent strands and to thereby cause the strands having relatively thick places therein to be attenuated to a greater extent than the thin places in adjacent strands to thereby substantially equalize the density of the strands throughout their lengths upon being drafted.

In the process of drafting strands of sliver or roving heretofore, the conventional types of top and bottom feed rolls have caused some improvement in the uniformity of the strands as they issued from the delivery rolls. However, to my knowledge, the variations in thickness or density of the strands have not been improved in excess of seventeen per cent. Experiments with the improved evener mechanism have improved the uniformity of the strands up to thirty-four per cent.

In the drawings and specification there has been set forth a preferred embodiment of the invention and although specific terms are employed, they are used in a generic and descriptive sense only, and not for purposes of limitation, the scope of the invention being defined in the claims.

I claim:

1. In a drafting mechanism having a frame and a plurality of successive sets of top and bottom drafting rolls driven at progressively increasing speeds for attenuating a plurality of strands of roving, sliver and the like; the combination of a driven common fluted bottom feed roll disposed in advance of a first of said sets of top and bottom drafting rolls, a plurality of relatively narrow brackets pivoted on the frame at a point in advance of the common bottom feed roll, a fluted top evener roll rotatably supported by each of said pivoted brackets above said common fluted bottom roll, yieldable means connected to each of said brackets for urging the corresponding evener roll into engagement with the common bottom feed roll, and each of said evener rolls being independently movable toward and away from said common bottom roll solely in accordance with the thickness of the strand at the nip of said evener roll and said common bottom roll.

2. In a drafting mechanism having a frame and a plurality of successive sets of top and bottom drafting rolls driven at progressively increasing speeds for attenuating a plurality of strands of roving, sliver and the like; the combination of a driven common bottom fluted feed roll disposed in advance of a first of said sets of drafting

rolls, a plurality of relatively narrow brackets pivotally supported on the frame at a point in advance of the common bottom fluted feed roll, a fluted top evener roll rotatably supported by each of said pivoted brackets above said common bottom roll, resilient means connected to each of said brackets for urging the corresponding evener roll toward the common bottom feed roll, each of said brackets comprising a substantially U-shaped trough having its upper surface disposed in substantial alignment with the junctures of the corresponding evener roll and the common bottom feed roll, a pair of ears extending forwardly from the side portions of the substantially U-shaped trough, a shaft carried by and extending between said ears and on which the corresponding evener roll is rotatably mounted, a common transverse bar disposed rearwardly of the common bottom feed roll, and means pivotally connecting the end of each of said brackets remote from the ears thereof to said transverse bar whereby said strands may be directed between the corresponding evener rolls and the common bottom roll through said trough.

3. In a drafting machine having a plurality of rows of bearing blocks each provided with a substantially U-shaped groove therein, a plurality of driven sets of top and bottom drafting rolls rotatably supported in some of said bearing blocks, the combination of a driven common bottom fluted feed roll disposed in advance of the sets of top and bottom drafting rolls and being journaled in the U-shaped grooves of others of the bearing blocks, a plurality of fluted relatively narrow evener rolls above the common bottom roll, a respective bracket for each of said evener rolls comprising a substantially U-shaped trough member having a pair of ears extending forwardly therefrom astride the corresponding evener roll, means rotatably supporting said corresponding evener roll between said ears, a common transverse bar disposed in advance of the common bottom roll, means pivotally connecting the rear ends of said brackets to said common transverse bar, said common transverse bar having a pair of arms, one each extending upwardly and forwardly at an angle from each end of the common transverse bar, each of said arms having an outwardly projecting journal portion integral therewith adapted to fit in the corresponding U-shaped groove of the corresponding bearing block in which the bottom feed roll is journaled whereby, upon adjustment of the bearing blocks for varying the position of the common bottom feed roll relative

to the sets of drafting rolls, the positions of the evener rolls will automatically be varied accordingly to thereby insure that the evener rolls are maintained in constant axial relationship to the common bottom feed roll, and

5 means resiliently biasing said pivoted brackets downwardly to resiliently urge the corresponding evener rolls toward the common bottom feed roll whereby individual strands may be fed through each U-shaped trough member and between the bottom feed roll and the corresponding evener roll in its course to the sets of top and bottom rolls.

4. In a drafting machine for drafting a plurality of strands of material having a plurality of rows of bearing blocks, each provided with a bearing groove therein, a 15 plurality of sets of top and bottom drafting rolls rotatably supported in some of said bearing blocks and said bottom drafting rolls being driven; the combination of a driven common bottom fluted feed roll disposed in advance of the sets of top and bottom drafting rolls and being 20 journaled in the bearing grooves of others of said bearing blocks, a plurality of fluted individual evener rolls positioned above the common bottom roll, an individual bracket independently supporting each of said evener rolls, a common transverse bar disposed in advance of the common bottom roll, means pivotally connecting said brackets to said common transverse bar, resilient means associated with said brackets and urging said individual evener rolls toward the common bottom roll, said individual evener rolls being movable away 25 from said common bottom roll solely upon and in accordance with variations in the thickness of the corresponding strand at the nip of said common bottom roll with the corresponding evener roll, means connecting the common transverse bar with the bearing blocks in which 30 the bottom feed roll is journaled whereby adjustment of said bearing blocks for adjusting the position of the common bottom feed roll relative to the sets of drafting rolls will cause a like adjustment of the individual evener rolls.

40.
